VACUUM NOZZLE

Filed July 20, 1925

UNITED STATES PATENT OFFICE

LEE W. DICEY, OF RICHMOND, CALIFORNIA, ASSIGNEE, BY MESNE ASSIGNMENTS, TO
STANDARD OIL COMPANY OF CALIFORNIA, OF SAN FRANCISCO, CALIFORNIA, A
CORPORATION OF DELAWARE

VACUUM NOZZLE

Application filed July 20, 1926. Serial No. 44,850.

This invention relates to vacuum nozzles, and is more particularly directed to a nozzle employed in connection with the filling of containers with volatile inflammable fluids, such as gasoline, distillate, and the like.

In the filling of containers, such as five gallon cans, with gasoline and other inflammable fluids, it is particularly desirable, if not absolutely necessary, to prevent the liberation of the fumes or vapors of the gasoline or other inflammable vapor from being permeated through the room in large quantities as such vapors or fumes are extremely noxious, that is to say, they are injurious to the health of the individuals working in the room and also create a great fire hazard.

It is desirable also to automatically fill such containers, first weighing the inflammable fluid with which the same is to be filled so that the volumetric measurements printed on the container will correspond with the true contents of the container and then discharging the weighed liquid into containers which are automatically conveyed and positioned under the discharge nozzle to receive the liquid. It is, therefore, an object of this invention to provide a vacuum nozzle which is particularly adapted for use in connection with automatic equipment for filling containers.

Another object of this invention is to provide a vacuum nozzle having means incorporated therewith which may be connected with or inserted into the container to provide a fluid-tight connection therewith so that all the inflammable volatile vapors liberated during the filling of such container may be drawn off to a suitable point of exposure.

Other objects and advantages of this invention will be apparent from the following detailed description of a preferred embodiment thereof, as illustrated in the accompanying drawings.

In the drawings:

Fig. 1 is a diagrammatic elevation of an automatic weighing and filling apparatus employing a nozzle illustrated diagrammatically in said elevation, embodying this invention.

Fig. 2 is an enlarged side elevation of a vacuum nozzle embodying this invention.

Fig. 3 is a central sectional side elevation thereof.

Fig. 4 is a top plan taken substantially on the line 4—4, of Fig. 3 of a vacuum nozzle illustrating the same with the packing-retaining neck removed.

In the preferred embodiment of this invention illustrated in the accompanying drawings, 1 illustrates a conveyor upon which a container 2, such as a five-gallon can, is conveyed to the point to be filled. 3 illustrates a vacuum nozzle having a discharge spout 4 which is adapted to fit within the bung or hole 5 of the container. The containers 2 are conveyed on the conveyor 1 in an inclined position so that as the container 2 is filled the air which is expelled therefrom will all flow towards the hole 5 of such container 2. 6 illustrates a conduit leading from any suitable point of storage or supply of the liquid with which it is desired to fill the container 2. The liquid is discharged into a weigh hopper 7, which may be of any desired or preferred type. A valve 8 is situated in the lower end of the weigh hopper 7 and when the same has received a predetermined weight of the liquid the valve head is lifted from its seat by means of the cable 9 which is wound on a drum 10 which drum is operated by means of a belt 11 passing over a pulley 12. The filling hopper 13 receives the weighted liquid from the weigh hopper 7 and is supported by means not herein illustrated. When the container 2 is in the position illustrated in Fig. 1 the nozzle 3, which is slidably mounted on spout 18 is dropped, by means not shown, so that the spout 4 of the nozzle 3 is inserted in the hole 5. The valve 14 of the filling hopper 13 is then opened to admit the liquid from the hopper 13 into the container 2.

The vacuum pump, diagrammatically illustrated at 15, is connected to the nozzle 3 and draws the vapors and air expelled from the container by the admission of the liquid from the container and delivers the same to any suitable point, not shown.

The vacuum nozzle 3 comprises a body 16 having a central filling duct or passage 17 adapted to receive the spout 18 of the filling hopper 13. The central passage 17 is re-

duced, as illustrated at 19, to approximately the size adapted to fit within the hole 5 of the container 2. The outer diameter of the spout 4 thereof is slightly smaller than the diameter of the hole 5 of the container 2.

6 A fume duct is provided, preferably in the form of an annular chamber located in the body 16 so as to surround the central passage 17 thereof. The chamber 17 is connected to the conduit 21 at 22. The chamber 20 is open at the lower end around the spout 4 of the nozzle 3, a plurality of spacing lugs 23 being provided to centrally place the discharge spout 4 in the hole 5 so that 10 there will be passages between the body 16 and the spout 4 through which the vapors and air liberated from the container 2 may be drawn into the chamber 20 by means of the vacuum pump 15. These openings maintain communication between the chamber 20 and the interior of the container while the same is being filled. As the containers 2 are in an inclined position on the conveyor 1, it is necessary that the means provided for 15 maintaining air-tight or fluid-tight connection of the nozzle that the containers 2 be at an inclined position and for this reason the lower end of the body 16 has a tapered or conical surface 24 operating as a seat upon 20 which a washer 25 of leather, rubber, or like material, is fitted and which washer is retained in position by means of a nut or cap 26, which nut or cap 26 is screw threaded to the offset 27 formed on the body 16. The 25 axis of the conical seat is inclined. The cap nut 26 is of larger central bore than the spout 4 of the nozzle 3 so as to permit the washer 25 to project outward therefrom so that when 30 the nozzle is lowered into engagement with the container 2 the portion of the washer 25 which extends from under the cap nut 26 will be engaged by the periphery of the hole 5 and a fluid-tight connection will be obtained between the nozzle 3 and the mouth of the 35 container 2 so that the vacuum maintained in the chamber 20 will act upon the gas and vapors liberated from or expelled from the 40 interior of the container 2.

Having fully described a preferred embodiment of this invention, it is to be understood that I do not wish to be limited to the exact details of construction herein set forth, which may, obviously, be varied in detail without departing from the spirit of the appended 45 claim.

50 I claim:

A vacuum nozzle comprising a body having a passage formed therethrough, a spout formed at the lower end of the passage, a 55 vacuum chamber surrounding the said passage, a plurality of lugs spaced around the periphery of the said spout for centering the spout in the inlet of a container with the vacuum chamber in communication with the interior of the said container, and means

60 mounted on the said body in inclined position for maintaining a fluid tight connection between the spout and a container supported in an inclined position.

65 Signed at Richmond, California, this 9th day of July 1925.

70 LEE W. DICELY.
